(57) **CLAIM**

The ornamental design for a vehicle tail light as shown and described.

DESCRIPTION

FIG. 1 is a perspective view of an embodiment of a vehicle tail light;

FIG. 2 is a front view of the embodiment of a vehicle tail light of FIG. 1;

FIG. 3 is a rear view of the embodiment of a vehicle tail light of FIG. 1;

FIG. 4 is a right-side view of the embodiment of a vehicle tail light of FIG. 1;

FIG. 5 is a left-side view of the embodiment of a vehicle tail light of FIG. 1;

FIG. 6 is a top view of the embodiment of a vehicle tail light of FIG. 1;

FIG. 7 is a bottom view of the embodiment of a vehicle tail light of FIG. 1;

FIG. 8 is a perspective view of the embodiment of a vehicle tail light of FIG. 1 installed in a vehicle;

FIG. 9 is a perspective view of a second embodiment of a vehicle tail light;

FIG. 10 is a front view of the embodiment of a vehicle tail light of FIG. 9;

FIG. 11 is a rear view of the embodiment of a vehicle tail light of FIG. 9;

FIG. 12 is a left-side view of the embodiment of a vehicle tail light of FIG. 9;

FIG. 13 is a right-side view of the embodiment of a vehicle tail light of FIG. 9;

FIG. 14 is a top view of the embodiment of a vehicle tail light of FIG. 9;

FIG. 15 is a bottom view of the embodiment of a vehicle tail light of FIG. 9; and,

FIG. 16 is a perspective view of the embodiment of a vehicle tail light of FIG. 9 installed in a vehicle.

The broken lines in FIGS. 1, 3 through 7, 9, and 11 through 15 depict portions of the vehicle tail light in which the design is embodied that form no part of the claimed design. The broken lines in FIGS. 8 and 16 depict environmental structure and form no part of the claimed design.
